ATTY'S.

UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

CRUSHER.

No. 851,390.

Specification of Letters Patent.

Patented April 23, 1907.

Application filed May 15, 1905. Serial No. 260,499.

To all whom it may concern:

Be it known that I, MILTON F. WILLIAMS, a citizen of the United States, residing at St. Louis, Missouri, have invented a certain new and useful Improvement in Crushers, of which the following is a full, clear, and exact description, such as will enable others skilled in the art to which it appertains to make and use the same, reference being had to the accompanying drawings, forming part of this specification, in which—

Figure 1 is a view in elevation of the hammers and hammer supports of a crusher and pulverizer constructed in accordance with my invention; Fig. 2 is an enlarged fragmentary elevation of the same; and Fig. 3 is an end view of the hammers.

This invention relates to the class of crushers and pulverizers, and one of the objects of the invention is to improve the construction of the disintegrating mechanism and particularly the hammers and their connecting supports.

Another object of the invention is to provide means whereby the hammers or beaters will be supported around an axis in staggered relation to each other and in such a manner that the material may be thoroughly acted upon.

Another object of the invention is to provide means for adjustably securing the hammers so as to provide for the wear incident to the continual operation of the machine, and to so provide these adjustments that the opposite hammers will be diametrically opposite to each other so that they will be balanced around the axis.

Other objects and advantages as well as the novel details of construction of this invention will be specifically described hereinafter, it being understood that changes in form, proportion and minor details of construction may be resorted to without departing from the spirit of my invention or sacrificing any of the advantages thereof.

The preferred embodiment of my invention as illustrated in the accompanying drawings includes a shaft 1 carrying a plurality of alternately arranged hammer sup-

ports comprising arms 2 and 3 which are 50 keyed to the shaft. These arms have central openings through which the shaft projects, said arms being approximately rectangular in form, and each alternate arm is at right angles to the adjacent one. 55

4 and 4^a designate curved series of openings in the ends of the respective arms, and these openings receive the connecting members 5 of the hammers 6. The hammers 6 on each arm are diametrically opposite to 60 each other but alternate with those on the adjacent arm. In other words, the hammers on the respective arms align with the adjacent arm and are of about the same thickness as said arms. It will be observed 65 that by this arrangement the weight of the hammers 6 will be evenly distributed around the axis of the shaft 1, and all of the material will be evenly acted upon, which material may be placed within a casing 7 having a 70 cage or grate 8 in the bottom thereof.

Having thus described my invention, what I claim as new and desire to secure by Letters Patent is:

In a device of the character described, the 75 combination of hammer supports comprising oppositely disposed connected arms secured to said shaft, an auxiliary pair of hammer supports comprising oppositely disposed connected arms also secured to said shaft and 80 extending at substantially right angles to the first mentioned arms, and hammers on each of said arms, the hammers on the arms of one pair being arranged upon the same side and the hammers on the arm of the 85 auxiliary pair being arranged upon the same side but the side opposite to that on which the first mentioned arms are mounted, whereby the hammers are in the same plane with the arms of the adjacent pair. 90

In testimony whereof, I hereunto affix my signature, in the presence of two witnesses, this 11th day of May 1905.

MILTON F. WILLIAMS.
